(57) **CLAIM**

The ornamental design for a coupe ride-on toy, as shown and described.

DESCRIPTION

FIG. 1 is a front perspective view of the design.
 FIG. 2 is a rear perspective view of FIG. 1.
 FIG. 3 is a front elevation view of FIG. 1.
 FIG. 4 is a rear elevation view of FIG. 1.
 FIG. 5 is a left side elevation view of FIG. 1 with the right side being a mirror image thereof; and,
 FIG. 6 is a top plan view of FIG. 1.
 The broken lines show portions of the coupe ride-on toy that form no part of the claimed design.
